UNITED STATES PATENT OFFICE.

VIKTOR MAX KOLBE, OF BERLIN, GERMANY.

DEVICE FOR RENDERING ADVERTISEMENTS LUMINOUS BY THE OPENING OR CLOSING OF DOORS.

Application filed November 1, 1926, Serial No. 145,647, and in Germany June 8, 1925.

There exist already devices for rendering advertisements luminous by the opening or closing of doors, the respective circuit or circuits being closed and opened by a cut-out actuated automatically by the respective door. Also constructional forms have been designed in which lamps located in a shop-window are supplied with current from a separate source of current, whereas a second source of current supplies current to a plurality of other lamps when a circuit-closing device inserted into a floor is actuated.

Now, in contradistinction to those known devices, the gist of the present new device resides therein that the circuit-closing device, or cut-out respectively, for the luminous advertisement or advertisements is connected up in shunt with a circuit for a continually shown luminous advertisement and is, besides, connected with a double switch in such a manner that the intermittently appearing luminous advertisement can be switched in either separately or together with the continually shown luminous advertisement whereby one of the two sources of current mentioned is saved.

The invention is shown diagrammatically and by way of example on the accompanying drawing on which Figure 1 is a total view of a plant designed according to this invention; Figure 2 shows a wiring diagram pertaining thereto, Figure 3 illustrates diagrammatically two sets of electric incandescent lamps arranged in symmetrical relation as when assembled on a sign board. Fig. 4 is a detail view of the door-operated switch showing its position when the door is closed. Fig. 5 shows the same switch when the door is open.

On the drawing, *a* denotes a frame which may be so designed as to be adapted to be suspended from chains *b*. If it is suspended in front of a shop window pane this latter may be protected from shocks for instance by rubber suckers *c* secured to the board and adhering to the pane by suction.

The frame *a* is provided with a plurality of incandescent lamps *d* distributed in any suitable manner, for instance as shown in Fig. 3, in which the lamps are distributed in two sets around the circumference of the frame. There are among these lamps three denoted with *e* which are those intended to burn continually, whereas the other lamps are to burn only as long as a certain door is open, the respective circuit being closed

when that door is open, and opened when that door is closed.

The letters of reference *f*, *g*, *h* denote an automatic cut-out comprising a metal strip *f*, a spring *g* and a button *h*. The cut-out device is secured to that side of the door frame to which the door is hinged. The parts *f* and *g* are conductive, but insulated from each other by a piece *i* of insulating material. The cut-out is inserted into the circuit *k* by means of its members *g* and *h*, and the circuit is broken as long as the free end of the spring *g* is kept off the metal strip *f* by means of the button *h*, this button being forced inwardly by the edge of the door when the latter is closed. When the door is opened, the circuit will be closed, provided, a switch *m m'* be in proper position therefore, as more fully dealt with

hereinafter.

The current is supplied to the lamps of the board either by stranded wires or by sliding contacts, as best suited in the given case.

o denotes a source of current, one pole of which is connected with one of the binding posts of a double-switch *m m'* which is shown in Fig. 2 in that position in which no circuit is closed. This is the day-position in which the luminous board is not illuminated. When the two movable conducting members of the switch which are conductively connected with each other have been turned to the right, upon the contacts *p* and *q*, the electric connections are as follows:

The current flows from the +pole of the source of current over the switch member *m'* and the contact *q* to the wire *r* which is connected with the three lamps *e*; these lamps are also connected with the wire *s* that is connected with the -pole of the source of current *o*. This circuit is independent of the cut-out *f*, *g*, *h*, and, therefore, independent of the opening and closing of the door operating said cut-out.

When the door is open and the circuit-closing device, therefore, closed (the switch member *m'* resting still upon the contact *q*) the current passes from the switch member *m'* to the switch member *m*, further over the contact *p*, through the wire *t*, the closed circuit-closing device *f*, *g*, *h*, the lamps *d*, and back to the source of current *o* through the wire *s*.

If, however, the switch members *m m'*

are shifted to the left the otherwise continually burning lamps *e* are switched off and only the lamps *d* are supplied with current as long as the door is open. The path of 5 the current is then: +pole of the source of current *o*, switch members *m* and *m'*, wire *k*, circuit-closing device *f*, *g*, *h*, lamps *d*, wire *s*. This circuit is interrupted when the door is closed.

10 The board *a* may have an inscription, as for instance "attention", "step" or the like, and instead of being suspended by chains or the like, as in Fig. 3, it may be firmly affixed to the respective door or the like.

15 I claim:

1. In combination with a door, an illuminated advertising device comprising in com-

bination, two electric circuits including a source of current for said circuits, a plurality of lamps in each circuit, a circuit-controlling mechanism in one of said circuits, said mechanism being closed when said door is open, and a double-pole switch, 20 said switch when in one position connecting both of said circuits with said source, and when in a second position connecting only 25 one of said circuits with said source.

2. An illuminated advertising device as claimed in claim 1, said circuit-closing mechanism being in series with the circuit 30 closed by said switch in said second position.

In testimony whereof I affix my signature.

VIKTOR MAX KOLBE.
